HYDRAULIC LOG BARKERS

Marion F. Fish, Everett, Wash., assignor to
Sumner Iron Works, Inc., Everett, Wash.

Filed Feb. 25, 1957, Ser. No. 642,041

2 Claims. (Cl. 239—184)

This invention relates to improvements in hydraulic log markers. More particularly, the invention has to do with the provision of means for and the directional control of the nozzle from which the water is discharged against the log for the removal of the bark.

It is the principal object of this invention to provide a barker having what is designated in the industry to which it pertains as a "swinging nozzle," in that the nozzle is mounted on the water-supply pipe for limited angular adjustment, thus to provide for changing the angle or direction of contact of the water jets with the log to best suit the particular operation at hand.

More specifically stated, it is the principal object of this invention to provide the water-supply pipe with a discharge nozzle that is mounted for angular adjustment, and to provide a hydraulic cylinder for effecting its adjustments, to which water under pressure from the water-supply line may be supplied under valve control for its operation.

Still further objects and advantages of the present invention reside in the details of construction and combination of parts embodied in the nozzle and its controls, and in their mode of operation, as will hereinafter be fully described.

In accomplishing the above-mentioned and other objects of the invention, I have provided the improved details of construction, the preferred forms of which are illustrated in the accompanying drawings, wherein:

Fig. 1 is a side view of a traveling log barker equipped with a swinging, or angularly adjustable nozzle with control mechanism embodied in the present invention.

Fig. 2 is a somewhat enlarged side view of the present nozzle and its hydraulic adjusting cylinder, indicating the extent of angular adjustment that can be made.

Fig. 3 is a horizontal section, taken on the line 3—3 in Fig. 2.

Fig. 4 is an enlarged sectional view through the nozzle and its mounting member taken on line 4—4 in Fig. 5.

Fig. 5 is a sectional view, taken on line 5—5 in Fig. 2.

Fig. 6 is an enlarged end view of the upper end portion of the nozzle mounting water supply pipe, showing the mounting of the solenoid valve thereon for controlling the nozzle adjustments.

Fig. 7 is a side view of the parts shown in Fig. 6.

Fig. 8 is a horizontal section taken on line 8—8 in Fig. 9.

Fig. 9 is a side view of the nozzle and valve mounting water supply pipe, with parts broken away to shorten the view, and with the pressure lines which connect the valve and nozzle controlling cylinder offset from their true positions for easier understanding of the connection.

Fig. 10 is an enlarged plan view of the collector rings and brushes employed in the electrical control of the solenoid valve.

Fig. 11 is a cross-section, taken on line 11—11 in Fig. 10.

Fig. 12 is a wiring diagram for the electrical controls for the solenoid valve.

2

Referring more in detail to the drawings:

For explanatory purposes, the present invention has been illustrated in connection with a log barker of the type of that shown in United States Patent No. 2,765,198, issued on Oct. 2, 1956. The barker illustrated comprises a base frame structure 10 supported by wheels 11 for travel on a track 12, beneath which track the log to be barked would be longitudinally disposed. Rigidly fixed on the base frame structure 10 is a vertical standard, or frame 13, to which laterally spaced, vertical guide rods 14—14 are fixed. Mounted on these rods, for movement upwardly and downwardly therealong, under control of means not herein shown, is a motor mounting carriage or base 15 within which a vertical section 16 of a water supply pipe line is mounted for axial rotation. Operatively joined to the upper end of pipe section 16 is an elbow jointed supply pipe line designated at 17, and fixed to its lower end is a vertically and downwardly extended length of water pipe 18. This extends slidably and rotatably through a bearing, which in Fig. 1 is designated generally by numeral 20, that is fixed in the base frame structure 10. At its lower end the pipe 18 is equipped with the present swinging nozzle, designated in its entirety in Fig. 1 by numeral 22.

Mounted on the motor base 15 is an electric motor 23 which has a geared connection, as indicated at 24, with the upper end of pipe 16, and it is through this motor and connection that the pipe 18 is adapted to be rotatably adjusted about its axis. Also, means powered by the motor is operable to raise and lower the carriage 15 and the pipe 18 accordingly to locate this nozzle in the most advantageous position with respect to the log being barked; this means not being illustrated herein.

The present barking operation contemplates that, after a log has been properly positioned beneath and longitudinally of the track, the barker is advanced on the track to a position locating the nozzle above and at one end of the log. Then water supplied under high pressure, through pipe line 17 and pipe section 16, is caused to be discharged through pipe 18 and nozzle 22 against the log. The nozzle is then rotatably and angularly adjusted to position it to effect the best results, and as the bark is removed, the log is rotated and the nozzle advanced therealong in the manner as explained in the previously mentioned patent.

The novelty of the present invention resides primarily in the nozzle; its mounting means and in the means for effecting and controlling its adjustments, characterized by a hydraulic cylinder that is mounted on the water supply pipe line closely adjacent the nozzle. The nozzle and its mounting will first be described, reference being directed particularly to Figs. 4, 5 and 9.

It is shown in Fig. 4 that the nozzle structure comprises as a part thereof, what is designated as the mounting T 25; this being a tubular fitting equipped at its upper end with an encircling flange 26 matching and fitted to a similar flange 27 formed on the lower end of the water pipe 18 and joined thereto in a water-tight connection by means of a plurality of bolts 28. The T 25 is relatively short, and at its lower end is formed with horizontally and oppositely directed tubular discharge hubs 29—29.

Rotatably fitted in a water-sealed joint, about each of the hubs 29 is the upper end of an elbow pipe section 30 which sections, at their lower ends are joined, respectively, to the opposite ends of the nozzle body 31. It is shown in Fig. 4 that the lower ends of the two elbow sections are flanged, as at 32, and that bolts 33 are applied through the flanges and threaded into the nozzle head to effect the connection.

The nozzle body 31 is hollow and the elbow pipe section 30 opens thereinto at its ends. The underside of

the body is longitudinally slotted and the slot is covered by a flat plate 34 secured by bolts 35, as in Fig. 4, and it is formed therealong with discharge orifices 36 from which the water jets are directed against the log for the barking operation in the form of an elongated brush. By rotary adjustment of the pipe 18, the direction of the brush relative to the longitudinal line of the log can be varied from transverse to lengthwise, and by rotary adjustment of the nozzle body about the horizontal axis of the two hub portions 29 of the mounting fitting 25, the angular direction of discharge can be varied as may be desired or required to obtain best results therefrom.

As a detail of construction, as shown in Fig. 5, the upper end portions of the two elbow sections 30-30 are tied together at opposite sides of the nozzle body by tie rods 36 that extend through lugs 37 that are cast on the upper end portions of the elbow sections; nuts 38 being applied to the ends of the rods and drawn tight.

For changing and for retaining any angular setting of the nozzle head between its limits of adjustment, the swingingly mounted portion is equipped with a pair of spaced rocker arms 40-40 as seen in Figs. 2, 5 and 9. At their inner ends, these arms are fixed rigidly to the upper end portions of the elbow sections, and at their outer ends are pivotally fixed by a pivot pin 41 to a cross-head member 42, located therebetween, and affixed to the lower end of a piston rod 43 extended downwardly from a hydraulic cylinder 44. It is shown in Figs. 2 and 3 that the hydraulic cylinder is pivotally supported between a pair of arms 45-45 that extend laterally from the upper end flange of the mounting T 25. The pivotal mountings of these parts permits the nozzle, under control of the cylinder, to be swung from the full line position in alignment with supply pipe 18 seen in Fig. 2, to the angular position in which it is shown in dotted lines.

Operation of the hydraulic cylinder 43 is under control of a solenoid valve 48 shown in Figs. 6, 7 and 9. This valve comprises a housing, which contains the solenoids and movable valve elements not shown. It is fixed by a U-bolt clamp 50 about the upper end portion of pipe 18, as shown in Fig. 9, and is adapted to be controlled by switch means, later described, located convenient to the operator. The valve is of conventional type, equipped with a valve element movable in one direction from a neutral position by energization of valve solenoid S¹ and movable in the opposite direction from its neutral position by a solenoid S². When at a neutral setting, no flow is permitted through the valve. A pressure supply conduit 55 leads to the valve from the supply pipe 18, as illustrated in Figs. 6 and 9, and pressure lines 56 and 57 lead from the valve, to upper and lower ends of the cylinder, respectively. Also, a discharge line 58 leads from the valve into the supply line through a bore 59 formed in the lower end flange of pipe 18. Under control of this valve, water under pressure can be admitted selectively to either end of the hydraulic cylinder and exhausted from the other end thus to cause a piston and piston rod movement that will effect the angular adjustment of the nozzle desired, then by closing the valve, the angular adjustment will be retained.

Because of the fact that the nozzle is below the bearing 20 in which supply pipe 18 is mounted and it is desired that the pressure conduits be passed through the bearing, these conduits are extended from the valve downwardly and closely along the sides of pipe 18 as has been shown in Figs. 6, 7 and 8. The bearing 20, as shown in Figs. 8 and 9, comprises complementary opposite side sections 20a and 20b, that are applied to opposite side of pipe 18 and joined together by bolts 60. Within this bearing is a cylindrical bushing 62 through which pipe 18 slidably extends and it is channeled, as at 63 for the passage of the conduits. Along one side the pipe 18 has a key 65

fixed thereto that is slidable in a channel 66 in the bushing.

The bearing 20, as seen in Fig. 9, is supported by and adapted to rotate in a housing 20x that is fixed to the base frame 10.

Electric circuit connections for the valve controlling solenoids S¹ and S² are as shown in Fig. 12 wherein electric current supply lines are designated at 70 and 71. Three contact rings 72-73 and 74 are supported from and about the flanged upper end of pipe 18 and are insulated therefrom by their supports. Circuit lines 75 and 76 lead from the rings 72 and 74, to one side of solenoids S¹ and S², respectively, and a circuit line 77 leads from the other sides of both solenoids to the ring 73. Brushes 79, 80 and 81 are mounted by a stationary bracket 82 for rubbing contact with the collector rings 72, 73 and 74, respectively. Circuit line 70 leads to brush 80 and circuit line 71 leads to a switch 85 whereby connection can be made selectively with lines 86 and 87 that lead to the brushes 79 and 81 respectively.

The arrangement of parts provides that when solenoid S¹ is energized, the valve is moved to allow pressure medium to be admitted to the upper end of the hydraulic cylinder. The cylinder piston is thus moved downwardly to swing the valve from the full line position of Fig. 9 toward the dotted line position. Closing of the valve, by deenergizing the solenoid, retains the nozzle setting. Likewise, application of pressure medium to the lower end of the cylinder, effected by energizing solenoid S², returns the nozzle toward downwardly directed setting. Thus, under control of the valve, the desired angular direction of discharge from the nozzle can be obtained and retained. By rotation of the pipe 18, the angular position of the brush of water jets as discharged therefrom, relative to the longitudinal axis of the log can be established.

In the present instance the showing of the barker is not intended to confine use of the present invention to any specific type of barker. It is the intent that the swinging nozzle be applied to any type of device for which it is applicable. Also, the valve means for its control and the electrical system may be modified or changed to best suit any particular operation.

What I claim as new is:

1. An apparatus for hydraulically debarking logs including a supporting frame, a vertically disposed supply pipe rotatably mounted in said frame, a nozzle mounted at the discharge end of said supply pipe for directing the water therefrom, said nozzle being swingingly mounted for adjustment to angular positions relative to the supply pipe, a hydraulic cylinder mounted on the supply pipe adjacent the nozzle, said cylinder including a piston rod operatively connected with said nozzle, a valve mechanism mounted on said supply pipe, a pipe line interconnecting said supply pipe and said valve mechanism, pipe connections between said valve mechanism and the hydraulic cylinder, a pair of electric solenoids interconnected with said valve mechanisms for controlling the operation of said valve mechanism whereby said valve is operable for effecting the application of water to the cylinder to effect and retain angular adjustments of the nozzle, and control means remote from said supply pipe for controlling operation of said solenoids to effect and retain the angular adjustments of said nozzle.

2. An apparatus for hydraulically debarking logs including a vertically disposed supply pipe, a nozzle mounted at the discharge end of said supply pipe for directing the water therefrom, said nozzle being swingingly mounted for adjustment to angular positions relative to the supply pipe, a hydraulic cylinder mounted on the supply pipe adjacent the nozzle, said cylinder including a piston rod operatively connected with said nozzle, a valve mecha-

nism mounted on said supply pipe, a pipe line interconnecting said supply pipe and said valve mechanism, pipe connections between said valve mechanism and the hydraulic cylinder, and a pair of electric solenoids interconnected with said valve mechanism for controlling the operation of said valve mechanism whereby said valve is operable for effecting the application of water to the cylinder to effect and retain angular adjustments of the nozzle, contact rings mounted on and around said supply pipe, and circuit lines being extended from said rings to the valve operating solenoids, and brushes mounted in position to individually supply current to said rings, and a manually operable switch controlling flow of electric current from a source of supply to the brushes.
